UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FILLING-REPLENISHING LOOM.

1,287,102. Specification of Letters Patent. Patented Dec. 10, 1918.

Application filed September 17, 1917, Serial No. 191,673.

To all whom it may concern:

Be it known that I, ALONZO E. RHOADES, a citizen of the United States, residing at Hopedale, county of Worcester, State of Massachusetts, have invented an Improvement in Filling-Replenishing Looms, of which the following description, in connection with the accompanying drawing, is a specification, like characters on the drawing representing like parts.

This invention relates to weft replenishing looms preferably of the automatic type and its object is to provide means for catching and thus retaining the trailing end of the abandoned filling carrier after its discharge from the shuttle in the operation of replenishment so that it will not be caught and carried by the shuttle or the fresh filling carrier into the cloth upon the succeeding pick.

This object is secured in the present invention by providing the chute which guides the discharging filling carrier with means for catching and retaining the trailing filling end which means is preferably provided by serrating the upper edge of the chute.

The invention also has for its object to provide a chute capable of yielding both forwardly and rearwardly from its normal position so that danger of breakage or a smash is prevented if the filling carrier be caught between the chute and a moving part of the loom during its discharge.

These and other objects of the invention will appear more fully from the accompanying description and drawings and will be particularly pointed out in the claims.

Figure 1 is an end elevation partially in vertical cross section of so much of an automatic weft replenishing loom of the Northrop type as is necessary to a disclosure of the present invention with a preferred form of the said invention embodied therein;

Fig. 2 is a front elevation of the transfer end of the lay shown in Fig. 1 together with a portion of the picker, the picker guide, and the chute.

The present invention is not concerned with the particular construction or operation of the general features of the loom to which it is applied. For convenience of illustration the invention is shown in the preferred form selected as embodied in an automatic filling

replenishing loom of the well known Northrop type.

In this type of loom the frame or loom side 1 supports at the transfer end of the loom a hopper stand 2 upon which is mounted a rotary hopper 3 carrying the supply of fresh filling carriers 4. The lay 5 carries at the transfer end the shuttle box 6, and the lay and shuttle box are provided with a vertical opening 7 therethrough to permit the downward discharge of an abandoned filling carrier when the shuttle is boxed at the transfer end of the loom.

A transerrer 8 is pivotally mounted on the hopper stand and provided with a dog 9 which upon the call for filling replenishment is lifted into the path of a bunter 10 carried by the lay thus causing the transerrer to force a fresh filling carrier, in this case a bobbin, from the hopper 3 into the shuttle and thereby discharge the abandoned or exhausted filling carrier or bobbin in the shuttle down through the opening 7.

The end of the filling extending from the abandoned filling carrier through the eye of the shuttle is usually, in feeler looms, severed by suitable mechanism adjacent the nose of the shuttle and this severed end must be drawn back through the eye of the shuttle and clear of the shuttle or it is liable to be caught by the shuttle or by the fresh filling carrier and dragged back into the shed and woven into the cloth causing an imperfection.

In this invention mechanism is provided to catch and retain this filling end as the filling carrier is discharged from the shuttle and prevent it from being dragged back into the shed by the shuttle or the fresh filling carrier.

For this purpose the chute which comprises a guiding plate 11 is serrated at its upper edge 12, the serrations preferably pointing away from the shed. When the lay beats up this chute contacts at its upper edge with the rear wall of the opening 7 and as transfer takes place the discharged bobbin forced out through the opening 7 slides down and is guided by the chute 11 into the usual receptacle placed beneath the hopper. As the lay starts on its return movement the trailing end of the filling is caught over the

serrated edge 12 of the chute and is caught and retained thereby so that it cannot be carried back by the shuttle or the fresh filling carrier into the shed.

5 The chute 11 is provided at its lower edge with journals 13 and 14 by which it is pivotally mounted on a stud 15 carried by a bracket 16 secured to the loom side. A helical spring 17 upon this stud is secured at 10 one end to the journal 14 of the chute and at the other end to a collar 18 fastened to the stud 15 by the cotter pin 19. This spring acts to hold the chute yieldingly in its normal position or about the position illustrated in Fig. 1 while allowing it to yield and swing forwardly. As the lay beats up 15 the edge of the chute contacts with the rear wall of the opening 7 and the chute yields forwardly keeping in contact with the said 20 wall.

If the filling carrier in descending on the chute should be caught by a moving part of the loom such as the bunter 10 while the lay was moving rearwardly it might get wedged 25 in against the chute 11 and break or injure the chute and this not infrequently happens. To prevent this the invention provides means for permitting the chute to yield rearwardly from its normal position. For this purpose 30 the bracket 16 carries at the rear of the stud 15 a socket support 20 in which is mounted a plunger 21. A helical spring 22, of greater tension than the spring 17, contained in the socket of the support 20 abuts at its upper 35 end the head of the plunger 21 and at its lower end the bottom of the socket thus serving yieldingly to project the plunger upwardly. A pair of nuts 23 are threaded on the lower end of the plunger 21 and serve to 40 limit and adjust the upward projection of the plunger. The adjustment is such that when the chute 11 is in its normal position it contacts with the plunger 21 and the nuts 23 contact with the bottom of the support 20. 45 If now upon the retracted movement of the lay the discharging filling carrier be caught or jammed against the chute the chute will yield rearwardly pressing the plunger 21 against the action of the spring 22 and thus 50 preventing breakage of the parts. A suitable guard 24 may be provided to prevent endwise movement of the filling carrier as it passes down the chute and is herein shown as rigidly supported from the lay by the 55 bracket 25.

Having fully described my invention, what I claim as new and desire to secure by Letters Patent is:

1. In a weft replenishing loom a lay provided with a shuttle box and having an opening therethrough to permit the discharge of the abandoned filling carrier, a chute located beneath said opening to receive and guide the discharged filling carrier, means for mounting said chute on the loom frame and permitting it to yield both forwardly and rearwardly from its normal position whereby the said chute may contact and yield forwardly from its normal position with the lay of the beat up and whereby the said chute may yield rearwardly from its normal position if the discharging filling carrier be caught between it and a moving part of the loom.

2. In a weft replenishing loom the combination of features as set forth in claim 1 wherein the said chute in addition is provided at its upper edge with filling retaining means to catch the trailing end of the discharging filling carrier.

3. In a weft replenishing loom the combination of features as set forth in claim 1 wherein the said chute in addition is serrated at its upper edge to catch the trailing end of the discharged filling carrier.

4. In a weft replenishing loom a lay provided with a shuttle box and having an opening therethrough to permit the discharge of the abandoned filling carrier, a chute mounted on the loom frame and located beneath said opening when the lay is in position for transfer, the said chute acting to receive and guide the discharged filling carrier, and filling retaining means upon the upper edge of the chute to catch the trailing end of the discharged filling carrier.

5. In a weft replenishing loom a lay provided with a shuttle box and having an opening therethrough to permit the discharge of the abandoned filling carrier, a chute mounted on the loom frame and located beneath said opening, when the lay is in position for transfer, the said chute acting to receive and guide the discharged filling carrier and serrated at its upper edge to catch the trailing end of the discharged filling carrier.

In testimony whereof, I have signed my name to this specification.

ALONZO E. RHOADES.
